US0D1090608S

(12) **United States Design Patent** (10) **Patent No.:** **US D1,090,608 S**
Mairs et al. (45) **Date of Patent:** **** Aug. 26, 2025**

(54) **DISPLAY SCREEN OR PORTION THEREOF WITH A GRAPHICAL USER INTERFACE**

(71) Applicant: **INSPIRE MEDICAL SYSTEMS, INC.**, Golden Valley, MN (US)

(72) Inventors: **Nicholas Mairs**, Minneapolis, MN (US); **Aaron Veicht**, Vadnais Heights, MN (US); **John Rondoni**, Plymouth, MN (US); **Donovan Fellows**, Lake Elmo, MN (US); **Brody Belland**, St. Louis Park, MN (US)

(73) Assignee: **Inspire Medical Systems, Inc.**, Golden Valley, MN (US)

(**) Term: **15 Years**

(21) Appl. No.: **29/888,595**

(22) Filed: **Apr. 3, 2023**

CLAIM

The ornamental design for a display screen or portion thereof with a graphical user interface, as shown and described.

DESCRIPTION

FIG. 1 is a front view of a display screen or portion thereof with a graphical user interface showing our new design; and, FIG. 2 is a front view of a second embodiment thereof. In the Figures, the outermost broken lines show a display screen or portion thereof and form no part of the claimed design. The remaining broken lines show elements of the graphical user interface that form no part of the claimed design. Shaded portions within broken lines form no part of the claimed design.

1 Claim, 2 Drawing Sheets
